UNITED STATES PATENT OFFICE.

WILLIAM DAVE GOODMAN AND FRANK TUTTLE, OF PARIS, TEXAS.

HARNESS-SADDLE.

SPECIFICATION forming part of Letters Patent No. 361,936, dated April 26, 1887.

Application filed December 1, 1886. Serial No. 290,381. (No model.)

To all whom it may concern:

Be it known that we, WILLIAM DAVE GOODMAN and FRANK TUTTLE, citizens of the United States, residing at Paris, in the county 5 of Lamar and State of Texas, have invented a new and useful Improvement in Harness-Pads, of which the following is a specification.

Our invention relates to an improvement in harness-saddles; and it consists in the peculiar construction and combination of devices, 10 that will be more fully set forth hereinafter, and particularly pointed out in the claim.

In the drawings, Figure 1 is a front elevation, partly in vertical central section, of a 15 harness-saddle embodying our improvements.

Fig. 2 is a detailed perspective view of the pad-former and the locking-plate therein. Fig. 3 is a transverse sectional view taken on line $x-x$ of Fig. 1. Fig. 4 is a detailed inverted perspective view of the locking-plate 20 detached from the pad-former. Figs. 5 and 6 are perspective views showing opposite sides of the link. Figs. 7 and 8 are detail views of the saddle-straps.

25 A represents the saddle proper, which is made of a leather strap of suitable width and thickness, and is provided with openings B, which are arranged at equal distances from the center of the saddle.

30 C represents the straps which form the back-band or girth, the said straps having near their upper ends openings D to align with the openings B, and at a suitable distance from the said openings D are made transverse slots 35 E, for the purpose to be hereinafter explained.

35 F represents the bridge, which is made of metal and is of the ordinary construction, and is provided with the check-rein hook G, and has openings H, adapted to register with the 40 openings D and B. Near the lower ends of the saddle-strap A are made vertical longitudinal openings I.

45 K represents links, which are made of metal and comprise the rectangular plates k, adapted to fit the openings I, and having at one end a shoulder or flange, k', projecting from one side, an eye, k'', projecting from the outer side of the said flange or shoulder and parallel with the plate k, but on a different plane, and from 50 the opposite end of the plate k, on the opposite side thereof, projects a T-shaped stud, k'.

L represents a pair of wooden pad-formers,

which form the cores or centers of the usual pads, and are preferably constructed of the form herein shown. These pad-formers are 55 each provided on one side with a recess, L', adapted to receive a locking-plate, M. The locking-plates are provided on their lower sides, at their edges, with depending flanges m', adapted to bear against the bottoms of the 60 recesses L', so as to leave a space between the opposing sides of the pad-formers and the locking-plates. Near the upper ends of the locking-plates are made openings N, adapted to register with the openings B, D, and H. 65 At a suitable distance below the said openings N are rectangular openings O, and near the lower ends of the locking-plate are T-shaped openings P.

R represents the tug-straps, and S represents the turrets, having the usual threaded shanks, T, and the nuts T' to screw thereon.

The manner of putting together the various parts hereinbefore described, in order to form 70 a saddle, is as follows: The links K have their 75 eyes k' passed through the transverse openings E in the straps C from the inner sides of the latter, and the said links are then caused to bear firmly against the inner sides of the said straps in a vertical position. The saddle-strap A has its ends arranged under the upper 80 ends of the straps C and in contact therewith, and the links K are caused to fit in the openings I near the lower ends of the saddle, and the plates of the said links correspond in 85 thickness to the thickness of the saddle, so that the said plates are flush therewith. When the links are fitted in the openings I, the openings B of the saddle and D of the back-straps register with each other. The locking-plates M 90 are then placed against the inner sides of the pendent portions of the saddle, and are locked to the links by passing the T-shaped heads or studs k' of the latter through the openings P of the locking-plates and then drawing the latter upwardly, so as to cause the shanks of the studs k' to enter the shoulders or offsets in the 95 said openings P. This brings the openings N in a line with the openings B and D. The bridge F is then placed on the upper side of the 100 saddle, with the arms or ends of the bridge bearing against the outer sides of the upper ends of the back-strap, and the openings H in the bridge registering with the openings B, D,

100

and N. The shanks of the turrets are then passed through the said registering openings and the nuts T' are screwed onto the threaded inner ends of the said shanks, thereby firmly 5 clamping the locking-plates against the inner sides of the saddle-strap, and also firmly clamping the saddle-strap, the back-strap, and the bridge together. This prevents the possibility of the locking-plates working longitudinally 10 on the inner side of the saddle, and thereby the links K are securely held in the recesses I of the saddle. Screws or rivets are then passed through suitable openings which are made in the lower portions of the links and through 15 the back-strap, so as to secure the latter firmly against the links. The tug-straps are then secured to the eyes of the links, as shown. The pad-former blocks L are then placed on the locking-plates so as to cover the inner sides 20 thereof, and also the inner ends of the turret-shanks, the nuts and the studs or heads k' thus preventing the said locking-plate and the projecting nuts and studs from working through the pad and injuring the horse's back. The 25 pads are then secured to the under side of the saddle and around the pad blocks in the usual manner.

We have omitted the pads in the accompanying illustration, and have only shown the 30 pad blocks or formers, as the pads are of the usual construction and are well understood by persons skilled in the art of making harness.

By thus providing the pad blocks or formers to cover the projections on the inner side of 35 the saddle the said projections are prevented

from working through the pads and injuring the horse's back, as before described, and the blocks or formers also serve a useful purpose in preserving the shape of the pads.

It will be observed that the various parts of 40 the saddle are secured together without friction, thus producing a saddle which is exceedingly strong and durable, which is not likely to rip or tear apart, and which can be manufactured at a very small cost. In the event 45 that any portion of the saddle becomes worn or broken, the saddle can be readily taken apart and the worn or broken portion replaced by a new one, thus greatly facilitating repairs and 50 also greatly reducing the cost thereof.

Having thus described our invention, we claim—

In a harness saddle, the combination of the link K, having the loop at one end and the headed stud k' projecting from one side, the 55 locking-plate having the opening P to receive and lock the said stud and thereby secure the link to the locking-plate, the latter being further provided with the depending flanges m' on one side, and the pad block or former having the recess to receive the locking-plate, substantially as described.

In testimony that we claim the foregoing as our own we have hereto affixed our signatures in presence of two witnesses.

WILLIAM DAVE GOODMAN.
FRANK TUTTLE.
